UNITED STATES PATENT OFFICE.

JUSTIN B. BULLIS, OF ANN ARBOR, MICHIGAN, ASSIGNOR TO THE ANN ARBOR MANUFACTURING COMPANY, OF SAME PLACE.

CURTAIN-FIXTURE.

SPECIFICATION forming part of Letters Patent No. 606,442, dated June 28, 1898.

Application filed November 22, 1897. Serial No. 659,497. (No model.)

To all whom it may concern:

Be it known that I, JUSTIN B. BULLIS, a citizen of the United States, residing at Ann Arbor, in the county of Washtenaw and State of Michigan, have invented certain new and useful Improvements in Curtain-Fixtures, of which the following is a specification, reference being had therein to the accompanying drawings.

10 The invention consists in the construction of a curtain-fixture, and particularly in the construction of the end supporting member of a curtain-pole upon which the curtain-rings are adapted to be moved.

15 In particular the invention consists in the construction of a curtain-pole having inwardly-extending ends, over which the rings are adapted to be moved, and a false end extension supported in the line of the pole, but 20 free therefrom, so as not to interfere with the movement of the rings, all as more fully hereinafter described.

25 In the drawings, Figure 1 is a perspective view of one end of a curtain-pole containing my invention; and Fig. 2 is a top plan view thereof, partly in section.

30 In the present state of the art it is well known that curtain-poles, such as A, may be bent at the ends, with the extensions B, to project to the wall, and over which the rings C are adapted to move. Such poles, however, as heretofore constructed have no end finish and do not have the pleasing effect of poles which (as has been usual in straight poles) 35 have an end ornament or extension beyond the curtain.

By my invention I am enabled to have the curved ends turning in to the wall and yet have the end ornament in line with the pole.

40 I have shown a pole A as made of metal, the arm B, also of metal, preferably cast, bent, or curved at the outer end into line with the pole and provided with a sleeve D, preferably screw-threaded on a head on the arm B and adapted to be adjusted longitudinally thereon to engage with the ends of the pole to secure the pole to the arm, and thus form, in effect, a straight pole with inwardly-extending securing-arms, over which the rings are adapted 45 to be moved. At the ends of the arms B are any securing means, preferably the plates F.

C are end extensions arranged substantially in line with the pole and supported in such position by arms, such as G, which I

have shown as extending from the plates F 55 free from the arms B, so as to admit of the free movement of the rings and leaving between the false ends and the arms or the pole a passage or opening for the rings. I find that I get the best structure by extending the 60 false end or ornament C on both sides of the arms G overlapping the arms B, so as in many positions to hide the fact that there is an opening between the pole and its false end.

While I have shown a specific construction, 65 I do not wish to be limited thereto, as I believe I am the first to support a false end extension to an outstanding curtain-pole having curved ends which allows free movement of the rings and gives the appearance of a 70 straight pole.

By the words "free from the pole" in the claims, referring to the false end pieces, I mean supported so that the rings may pass 75 between the pole and the end piece.

What I claim as my invention is—

1. The combination with a curtain-pole having inwardly-extending supporting-arms at the ends forming continuations of the pole over which the rings are adapted to be moved, 80 of false end pieces supported free from the pole and in the line of the pole proper, substantially as described.

2. The combination with a curtain-pole having inwardly-extending supporting-arms 85 at the ends forming continuations of the pole over which the rings are adapted to be moved, and a securing-plate at the end of these arms, of false end pieces in line with the pole proper, but separated therefrom to allow of the passage of the rings between, and arms projecting 90 from the securing-plate supporting said false end pieces.

3. In a curtain fixture, the combination with the curtain-pole having the curved ends 95 for the purpose described, of the arms G extending out beside the curved arms of the pole and the false end pieces C forming apparent end extensions of the pole, projecting on both sides of the arms G, for the purpose 100 described.

In testimony whereof I affix my signature in presence of two witnesses.

JUSTIN B. BULLIS.
